UNITED STATES PATENT OFFICE.

JAMES H. EASTON, OF ROCHESTER, MINNESOTA.

SNAP-HOOK.

SPECIFICATION forming part of Letters Patent No. 310,035, dated December 30, 1884.

Application filed May 23, 1884. (No model.)

To all whom it may concern:

Be it known that I, JAMES H. EASTON, a citizen of the United States, residing at Rochester, in the county of Olmsted and State of Minnesota, have invented certain new and useful Improvements in Snap-Hooks; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a perspective view of my snap-hook, and Fig. 2 is a vertical sectional view of the same.

This invention has relation to snap-hooks; and it consists in the construction and novel arrangement of parts, as hereinafter set forth, and pointed out in the appended claim.

In the accompanying drawings, the letter *a* designates the curved body of the snap, which is made broad on the inside and at the bearing-point *b*, so that it will afford a sufficient engagement for the end of the tongue, and that there will be no slipping of the tongue past the bearing. At its base the body *a* is grooved on the inside at *c* in proper form to receive the flat curved spring *d*, one end of which is seated in the groove *c*. The spring *d* is broad and flat, and its bend or convexity

e is downward. The tension of this spring is strong, so that it will act promptly and firmly.

g represents the tongue, which is pivoted to the body at *h*. Its inside wall is grooved at *k* to receive the long arm or branch *l* of the flat spring *d*. The outer face of the tongue is raised to form a knuckle or prominence, *m*, having angular edges *v*, easily recognized by the touch, so that the snap can be easily opened with gloves or mittens on the hands, even when the tongue is frozen to the hook. It also facilitates the manipulation of the snap in the dark. This prominence on the tongue also acts for a guide in introducing a ring into the snap, and forms an important feature in the invention.

What I claim, and desire to secure by Letters Patent, is—

The broad snap-hook body *a*, grooved inside to receive the bent flat spring *d*, and the broad tongue *g*, also grooved to engage the long branch of the spring, and having the knuckle or prominence *m* on its face, whereby it may be readily recognized by the touch, substantially as specified.

In testimony whereof I affix my signature in presence of two witnesses.

JAMES H. EASTON.
